UNITED STATES PATENT OFFICE.

CHARLES F. KETTERING AND WILLIAM A. CHRYSST, OF DAYTON, OHIO, ASSIGNEES TO
THE DAYTON ENGINEERING LABORATORIES COMPANY, A CORPORATION OF OHIO.

ENGINE STARTING DEVICE.

1,273,870.

Specification of Letters Patent. Patented July 30, 1918.

Original application filed July 14, 1913, Serial No. 778,934. Divided and this application filed February 9, 1916. Serial No. 77,346.

To all whom it may concern:

Be it known that we, CHARLES F. KETTERING and WILLIAM A. CHRYSST, citizens of the United States of America, residing at 5 Dayton, county of Montgomery, and State of Ohio, have invented certain new and useful Improvements in Engine Starting Devices, of which the following is a full, clear, and exact description.

10 This invention relates to a system of devices adapted for supplying power to start an engine, and the engine when thus started, is arranged to store up power for similar future starting operations, and this same 15 power source may then be used to supply current for the ignition system of the engine, and for any other purposes which may be desired.

The present application is a divisional 20 of our copending application, Serial No. 778,934, filed July 14, 1913, now Patent 1,241,990, Oct. 2, 1917, wherein a system of electrical generation, distribution, and control has been shown, described and claimed.

25 Up to the time of the present invention, practically all systems embodying starting devices of the electrical type, such as, for instance, as are included in the copending applications of C. F. Kettering, filed April 17, 1911, 30 Serial No. 621,512; now Patent 1,171,055, Feb. 8, 1916, filed September 19, 1912, Serial No. 721,237; now Pat. 1,240,348, Sept. 18, 1917, and the issued U. S. patent of Charles F. Kettering No. 1,150,523, comprised in general a 35 source of current, for instance, an accumulator or storage battery, and a motor and a generator, either combined in a single unit or embodied in separate and independent units. The above mentioned units generally have electrical connections between the 40 electric machine, or machines, and the storage battery, and mechanical connections between the said machine or machines, and the engine, together with controlling mechanism which comprises a switch unit for selecting the electrical connections and any 45 suitable means for controlling the mechanical connections.

Now, it is among the objects of the present 50 invention to simplify this controlling mechanism, and to eliminate certain of the units of the system, by so constructing, arranging, and combining other elements thereof, which are already employed to perform

given functions, that they will be capable of 55 operation, to perform not only their own original functions, but also the functions of the eliminated elements or mechanisms.

In the issued U. S. patent of Charles F. Kettering, No. 1,150,523, it is set forth that 60 one of the objects of the invention is to secure a preliminary movement of the electric machine, in order to facilitate the shifting of the connections between the said machine and the engine, so as to connect the 65 machine to the engine for starting purposes.

One of the objects of the present invention is to secure this preliminary movement of the electric machine by the operation of 70 a movable commutator brush, having means associated therewith to cut down the normal flow of current and thereby impart an initial movement to the electric machine, previous to the normal starting operation of the 75 machine.

One manner of carrying out the above object is to provide a movable commutator brush, including a plurality of relatively 80 movable elements. A resistance unit is associated with said elements in such a manner that an initial movement of this commutator brush will tend to close the circuit through the electric machine with this resistance in series in said circuit, this initial 85 operation of the machine as a motor tending to facilitate the mechanical connecting up of the electric machine to the engine.

Now, upon a further movement of the elements of the commutator brush, this resistance will be short-circuited and the main 90 motor circuit closed, whereby a full flow of current will pass through the motor, and thus effect the actual starting operation of the motor.

95 Further objects and advantages of the present invention will be apparent from the following description, reference being had to the accompanying drawings, wherein preferred forms of the present invention 100 are clearly illustrated.

In the accompanying drawings:

Figure 1 is a top plan view of a portion of the chassis of an automobile, showing the engine and electric machine, with the mechanical connections for coupling the electric machine and engine together.

105 Fig. 2 is a view partly diagrammatic and

partly structural of one form of the present invention; the structure of the vehicle and its chassis being eliminated, except for one side frame, for the sake of clearness.

5 Fig. 3 is a view in side elevation of the electric machine disclosed in Fig. 2, certain parts thereof being shown in section for the sake of clearness.

10 Fig. 4 is a detail plan view of certain of the mechanical structure shown in Fig. 3, and,

Fig. 5 illustrates a modified form of the brush holder shown in Figs. 2 and 3.

Referring to Fig. 1 of the drawings, the 15 numeral 20 designates the side frames of the chassis, while the numeral 21 indicates the engine, provided with the flywheel 22, having gear teeth 23 cut on its periphery.

The dynamo electric machine, which may 20 be termed the prime mover of the present invention, is designated by the numeral 24, and is adapted to be driven as a generator, during the normal operation of the engine, by means of the timing gears 25 and shaft 25 26, as is clearly shown in Fig. 1.

The location and arrangement of the dynamo electric machine is substantially the same as shown in the co-pending application, Serial No. 721,237, filed September 19, 30 1912; and the issued U. S. patent of Charles F. Kettering, No. 1,150,523; but it will be understood that this unit may be located on any part of the machine, the only restriction being that it be in such a position that 35 it will efficiently perform the desired and intended functions.

The lighting and ignition systems, and the circuits and devices therefor, have been clearly described, illustrated and claimed in 40 our co-pending application, Serial No. 778,934, filed July 14, 1913, and therefore no further description or illustration of these features is deemed necessary in the present application.

45 In Fig. 2 there is illustrated an electric machine of what may be termed the dynamo electric machine type, which may have its field and armature windings so arranged and constructed that it may be operated as 50 a generator for the purpose of charging the accumulator or providing current for ignition or lighting purposes, and again, as a motor for starting purposes.

55 Referring particularly to Fig. 2, one terminal 27 of the battery 28, is connected to the frame 20 of the chassis, while the other terminal of the battery leads through the wire 29, directly to the terminal 30, which is secured to but insulated from the dynamo 60 electric machine. This wire 29 constitutes what may be termed the common connection between both the motor and generator windings of the electric machine and the storage battery.

65 Referring to diagrammatic Fig. 2, it will

be noted that the wire 29 leads to a terminal 30 which is secured to the frame of the dynamo electric machine. This terminal is insulated from the frame in any suitable manner, as by washers 31 and the sleeve 32. 70

The opposite end of the terminal 30 is connected to one end 33 of the heavy or series motor winding 34, and also has a connection with the comparatively high resistance wire 35, which leads to the contact plate 36 of the 75 cut-out relay 37, which is included in the generator circuit.

Referring to Fig. 2, the opposite end of the series winding 34 is connected to the commutator brush 38. This brush is normally mounted so as to be in contact with the commutator at all times.

The opposite brush 39, however, is normally maintained out of contact making position with respect to the commutator, but is 80 so mounted that it may be depressed to engage or contact with the commutator.

The holder of brush 39 is divided into two elements 40 and 41, insulated from each other, but capable of independent movement 90 to a certain degree. The element 41 is pivotally mounted to any part of the generator frame and is electrically connected thereto. These two elements, that is, the element 40 and the element 41, are normally maintained 95 apart by means of a coil spring 42, which in Fig. 3 not only functions as a spring but also is composed of resistance material for the purposes hereinafter described.

In the modified form shown in Fig. 5, the 100 means for maintaining the elements 40 and 41 apart, is shown as comprising simply a coil spring 43, while a separate resistance unit 44 electrically connects the element 40 to the element 41. In this form, it is necessary that the spring which is interposed between the two elements be insulated from the element 41, so as to prevent the passage of current therethrough.

The portion or element 40 of the brush 110 holder is provided with an angle arm 45, which carries a roller 46 positioned in a slot 47, formed in one end of the lever 48. This lever 48 in turn is pivotally secured as at 49, while its opposite end is connected to 115 an operating rod 50, which extends rearwardly and may be secured to any suitable operating pedal 51. This rod 50 may be directly connected to a shaft 52, which carries the pedal 51 or which may be secured 120 thereto by means of a magnetic latch connection, such as is described in the issued U. S. patent of Charles F. Kettering, No. 1,150,523.

This same operating rod 50 is connected 125 to the shiftable gearing 53, which comprises a large pinion 54 and a small pinion 55, mounted adjacent to the armature pinion 56, which is carried on one end of the armature shaft 57.

This gearing 53 is adapted to be shifted into engagement with the armature pinion 56 and the flywheel gearing 23, and forms the driving means between the electric machine, when operating as a motor, and the flywheel of the engine.

It has been found advisable to provide some means for imparting a supplemental or initial movement to either the shiftable 10 gearing 53 or to the armature and its pinion, during the shifting of the gearing 53, so as to facilitate its connection with the armature pinion 56, and the flywheel teeth 23. That is, it has been found that there is a 15 tendency, under certain conditions, for the end faces of the pinions 54 and 55 to conflict with the end faces of the teeth of the armature pinion 56, and the teeth of the flywheel gearing 23, and under certain 20 circumstances, prevent the ready enmeshment of the above mentioned parts.

However, by imparting a relative movement to certain of these parts, as for instance, the armature pinion 56 and the shiftable gearing 53, any conflicting of the end faces of the teeth may be readily overcome and the gears easily enmeshed.

By describing the operation of the system shown in the accompanying drawings, it is 30 thought that the sequence of operations, and the manner in which they are secured, will be readily apparent.

When it is desired to operate the electric machine as a motor for starting purposes, 35 the main operating pedal 51 is first depressed. The depression of this main operating member will draw the rod 50 rearwardly in the direction of the arrow 58 shown in Figs. 2 and 3, and this will tend 40 to couple up the electric machine to the engine, by enmeshing the gearing 53 with the armature pinion 56 and the toothed portion 23 of the flywheel.

It will be understood, however, that the 45 enmeshment of the above mentioned gearing will not take place until after a slow initial movement has been imparted to the armature of the electric machine. This initial movement of the electric machine as a motor 50 is secured by the operation of the movable motor commutator brush. The initial movement of this brush and its holder will tend to break the generator circuit and will then 55 be in such position that neither the generator circuit or the motor circuit will be closed. However, upon continued movement of the operating member, the motor 60 brush 39 will be brought into engagement with the motor commutator, and this, of course, will establish the motor circuit.

It will now be obvious by referring to Fig. 2 that all current flowing through this established motor circuit, must necessarily pass through the following circuit: from 65 the battery 28, through the wire 29, to the

terminal button 30, thence through the series field coil 34, to the stationary commutator brush 38, across the armature to the movable brush 39 and thence through the resistance unit 42 to the other element of the 70 motor brush holder 41; thence to the ground connection 59 of the generator frame, back to the opposite side of the battery, via ground connection 60.

On a continued movement of the rod 50 75 in the direction of the arrow 58, see Figs. 2 and 3, the element 41 of the movable brush holder will be depressed further, relative to the commutator and also to the element 40 of the brush holder, which of course 80 is already in contact with the motor commutator.

Now, as soon as the portion 41 of the brush holder contacts with the portion 40, the resistance unit 42 will be short-circuited 85 and thus the full flow of current through the motor circuit will be effected.

In Fig. 3 it will be noted that the separate resistance unit is eliminated by combining this resistance unit directly with the 90 spring 42, which normally tends to support the two elements of the movable motor commutator brush.

Now, as soon as the engine has become 95 self-actuating, the operator will release the pedal 51 and permit the gearing 53 to return to its normal position, and also to permit the lever 48 to act on the movable commutator brush 39, in such a manner as to 100 return the same to its normal position, such as is shown in Figs. 2 and 3.

Any suitable arrangement of springs, (not shown), may be provided for returning the main operating member to its normal position as soon as it is released by the operator; these spring arrangements being 105 clearly described and shown in the heretofore referred to co-pending applications and the issued patent.

In view of the fact that the operation of 110 the electric machine as a generator does not form a part of the present invention, no description of the circuit arrangements and the associated devices is deemed necessary 115 in the present application, inasmuch as these circuits and devices have been fully shown, described and claimed in our co-pending application, Serial No. 778,934, filed July 14, 1913.

While the form of mechanism herein 120 shown and described constitutes a preferred form of embodiment of the invention, it is to be understood that other forms might be adopted, all coming within the scope of the claims which follow.

What we claim is as follows:

1. In a starting device, the combination with an engine and a motor adapted to be used for starting purposes, said motor having a set of commutator brushes and brush-

holders, one of said brush-holders comprising two independent elements insulated from each other; of a resistance unit electrically connecting the independent elements of said brush-holder; and means for operating one of said elements to cut out the effect of the resistance unit.

2. In a starting device for internal combustion engines, the combination with an engine and a motor, having a commutator and set of commutator brushes, one of said brushes having a brush-holder, comprising two independent elements insulated from each other; of an accumulator electrically connected with said motor; a resistance unit electrically connecting the independent elements of said brush-holder; and means for moving both of said elements of the brush-holder to close the circuit connections initially through said resistance and by continued movement to short-circuit the said resistance element.

3. In electric machines, the combination with an armature having a commutator and brushes, one of said brushes having a brush-holder consisting of two independent and insulated elements, and movable relative to each other; of a resistance unit electrically connecting said elements of the brush-holder; and a main operating member for moving one element of the said brush-holder into contact with the other element to short-circuit the said resistance.

4. In electric machines, the combination with a commutator brush and brush-holder comprising separate insulated elements; of a resistance unit electrically connecting said elements of the brush-holder; and means for moving one element of said brush-holder to cut out said resistance.

5. In electric machines, the combination with a commutator brush and brush-holder, said brush-holder comprising two independent and insulated elements; of a resistance unit electrically connecting said elements and resiliently separating the same; and means for moving one element of said brush-holder into contact with the other to cut out said resistance.

50 6. In a starting device for engines, the combination with an engine of an electric motor; shiftable mechanical connections between said engine and motor; a storage battery having circuit connections adapted to be connected with said motor; a commutator brush included in said circuit connections, but normally maintained in position to break one of said connections, said commutator brush comprising a plurality of elements.

and a resistance associated therewith; and a common operating member capable of an initial movement to actuate said commutator brush to close one of said circuit connections through the resistance to effect the operation of the motor at a slow initial speed, and capable of a second movement to shift the mechanical connections to couple up the motor and engine.

7. In a starting device for engines, the combination with an engine of an electric motor; shiftable mechanical connections between said engine and motor; a storage battery having circuit connections adapted to be connected with said motor; a commutator brush included in said circuit connections, but normally maintained in position to break one of said connections, said commutator brush comprising a plurality of elements and a resistance associated therewith; and a common operating member capable of an initial movement to actuate said commutator brush to close one of said circuit connections through the resistance to effect the operation of the motor at a slow initial speed, and capable of a second movement to shift the mechanical connections to couple up the motor and engine, and capable of a third movement to actuate one of the elements of said brush, relative to the other to short-circuit said resistance, whereby the electric machine may operate for starting purposes.

8. In a starting device, the combination with an engine, of a motor adapted to be coupled thereto for starting purposes; an accumulator; electrical connections between the accumulator and the motor, but normally disconnected; a movable device for completing the circuit between the accumulator and motor, comprising movably mounted elements insulated from each other, and a resistance element connected between the said elements; and an operating member for shifting said movable device to initially close the circuit through the resistance, and adapted by continued movement to cut out said resistance by bringing said movably mounted elements into contact with each other.

In testimony whereof we affix our signatures in the presence of two subscribing witnesses.
